CLAIM

The ornamental design for a display screen with graphical user interface, as shown and described.

DESCRIPTION

FIG. 1 is a front view of a display screen with graphical user interface showing our new design; and,

FIG. 2 is an enlarged view of the claimed portion as shown in FIG. 1 with selected environment removed for clarity purposes.

The uneven-length broken line defines the bounds of the claimed design and forms no part thereof. The even-length broken line showing of the text, various lines and regions, and the remainder of the display screen and graphical user interface forms no part of the claimed design.
